UNITED STATES PATENT OFFICE.

ROWLAND RUSHWORTH HIRST AND ARNOLD HIRST, OF HALIFAX, ENGLAND.

TENNIS POST.

Application filed August 7, 1922. Serial No. 530,376.

To all whom it may concern:

Be it known that we, ROWLAND RUSHWORTH HIRST and ARNOLD HIRST, subjects of King George V of Great Britain, residing at Halifax, in the county of York, England, have invented a new and useful Improvement 5 in Tennis Posts, of which the following is a specification.

This invention relates to the posts used to support the net in the game of tennis.

As is well known, these posts carry means to strain between them a wire or cord to which the net is attached, and in order that the upper edge of the net may be horizontal, 10 the straining effect on the net wire or cord must be very considerable.

It is necessary, therefore, that the posts be made very strong, but at the same time this strength cannot be provided at the expense 15 of weight, that is to say the post must not be too heavy to be handled comfortably by a groundsman or player.

The posts are commonly made of wood, and notwithstanding the most careful selection 20 and seasoning of the material, breakage and distortion of these wooden posts, under the great strain imposed upon them, very frequently occurs.

Hollow metal posts have been employed 25 in order to get the requisite strength, but as it is desirable that the upper ends of the posts shall have a rounded or spherical shape it has hitherto been necessary, in order to obtain this, to insert into the upper end of 30 a metal tube a plug of metal or wood having the desired external contour and secured by brazing or other means.

Certain constructions or types of net-straining gear also call for the fitting of a 35 guide pulley for the net wire centrally of the top of the post, and to enable this to be done in the case of a tubular metal post a plug or fitting of some description has had to be employed.

The object of this invention is to provide a 40 metal post approximately in diameter the ordinary wooden post and having a rounded or spherical head or upper end integral with the metal of which the post is composed. The thickness of such rounded or spherical 45 upper end can thus be made or kept the same as that of the body, and the weight of the post be kept at a practical amount, such head also having provision if required, for 50 the fitting of a guide pulley centrally of the

post without the application of any fitting or cap of any kind.

In order to enable the invention and the manner in which it is carried into practice to be clearly understood, reference will be 60 made to the accompanying drawing in which

Fig. 1 illustrates the initial stage of production of one of the improved posts;

Fig. 2 shews alternative sections of tubing suitable for the purposes of the invention; 65

Fig. 3 illustrates in elevation a completed post according to the invention as arranged to accommodate a winding barrel inside the post;

Fig. 4 is a section on the line A—A Fig. 70 3; and

Fig. 5 illustrates the manner in which the spherical or rounded head of the post is formed.

According to, and for the purposes of, the 75 invention a tube *a* of a suitable ductile metal, say of steel, of the proper diameter and of the requisite length is taken, and at the end which is to form the top of the post there are cut out on diametrically opposite sides of 80 the tube, two portions of the approximate shape illustrated at *b* in Fig. 1. The width of the gap at the apex is approximately that of the guide pulley to be subsequently accommodated.

The end of the tube having been thus prepared it is heated, and on the proper working heat being attained, there is inserted 90 into the tube a mandrel or plug *c* the *c'* of which is rounded or curved to the radius of the post less the thickness of the metal so that said plug corresponds to the inner surface or section of the finished head.

The opposite end of the plug or mandrel comes flush with the lower end of the tube 95 or has a collar or enlargement *c*² against which the end of the tube bears.

The plug *c* having been inserted, the tube is then placed into a die *d* having a rounded or curved inner end *d'* corresponding to the 100 exterior shape of the finished head. Pressure is applied by any suitable means such as a screw press, lever press, drop hammer or the like to close the die upon the two leaves or portions *a'*, *a'* of the tube end, and cause them to be curved inwardly and moulded to the shape of the die.

The mandrel *c* or die *d* may have a print 105 to fashion the slot *e* for the reception of the guide pulley, but in practice it is found 110

preferable to so proportion the cut out portions *b* that the closing in of the tube end by the die will leave a slot of somewhat narrower width than is required, which slot is then enlarged and accurately finished by milling or like operation.

If no provision is required to be made for a guide pulley in the post head, the cut out portions *b* are made smaller by an amount which will cause the edges of the leaves or portions *a*, *a'* to nicely abut and make a good joint under the action of the die. Such meeting portions may be suitably depressed to form a central groove across the post head for the cord to rest in, and the meeting edges of the leaves, if so formed into a groove, are preferably brazed, or otherwise joined to prevent any liability of damage to the cord.

Through unequal contraction of the metal when cooling, a certain amount of distortion from the true curvature may be apparent after the first pressing operation, in which case the post head is re-heated and subjected to a second pressing operation in a finishing die to leave it of true curvature.

After the post head has been formed as above set forth and the plug or mandrel removed, the slot *e* is milled out to the exact shape required, and an opening *f* cut, if desired, in the side of the post to admit of the insertion of a winding barrel. Openings *g*, *g* and *h*, *h* are also formed in the post, to receive the spindles of the guide pulley and winding barrel, if the post is fashioned to receive these parts.

By the method and means above set forth, there can be produced what has hitherto

been unattainable, namely a tubular steel or other metal tennis post having a rounded or spherical upper end or head integral with and of the same thickness as the body of the post, and it is further rendered possible to make provision, integral with a tubular metal post, for a centrally disposed guide pulley, to apply which it has hitherto been necessary to employ a separate cap or fitting.

Having thus described our invention, what we claim as new and desire to secure by Letters Patent is:—

1. A tennis post formed of a straight cylindrical tube of ductile metal provided with longitudinal notches having curved converging sides, said notches being formed in the upper end of the tube and the metal between the notches being bent to hemispherical form so that the two notches form a single continuous opening, the hemispherical end portion of the tube being of the same diameter and thickness as its main portion and having holes for receiving the spindle of a guide pulley.

2. A tennis post as set forth in claim 1, and having also an opening of greater width than the said opening and formed longitudinally in the main portion of the tube and communicating at its upper end with one end of the aforesaid opening, and the main portion of the tube having holes for receiving the spindle of a winding barrel.

In testimony whereof we affix our signatures.

ROWLAND RUSHWORTH HIRST.
ARNOLD HIRST.
